DOUBLE WARP KNITTING MACHINE

Herbert Wirth, Hartmannsdorf, near Chemnitz,
GermanyApplication February 13, 1937, Serial No. 125,660
In Germany February 22, 1936

2 Claims. (Cl. 66—86)

The present invention relates to a double warp knitting machine and more particularly refers to a novel arrangement of the sinker bar.

Hitherto double warp knitting machines are provided with a special shaft carrying the sinker bar. By means of corresponding cams the sinker bar is moved in its operative direction. With this construction the sinker bar must, by a corresponding formation of the cam, be held in its 10 position until its period of operation begins. During the time the needle bar is, for the purpose of lapping, moved upwardly and then again downwardly to the locking-in point, the sinker bar must be placed in a position of rest. Only 15 after this movement of the needle bar is carried out, the operation of the sinker bar is started.

According to the invention the cam levers, carrying the sinker bar by means of double-armed levers pivotally connected to them, are arranged upon the same shaft as the needle bar lever. The mode of operation thereby is considerably simplified. Due to the arrangement of the needle bar and the sinker bar upon a common shaft, cams with a smaller lift are required, whereby a more reliable operation, a 20 smooth running of the machine and therefore a higher number of revolutions is obtained.

In the accompanying drawing one construction according to the invention is somewhat diagrammatically shown by way of example.

Fixed upon the needle bar shaft 1 are the levers 3 carrying the needle bar 2. The levers 3 are moved in well known manner by means of cams not shown in the drawing which are fixed upon the cam shaft 4.

Upon the shaft 1, carrying the needle bar 2, the cam levers 6 for the sinker bar 10 also are

pivotedly arranged and these cam levers 6 also are moved by cams not shown in the drawing and fixed upon the cam shaft 4. Journalled in bearings 7 of the cam levers 6 are levers carrying the sinker bar 10. These levers are formed as double-armed levers 8, 9. The arms 8 of the double-armed levers 8, 9 carry the sinker bar 10. The arms 9 of the double-armed levers 8, 9 are, by means of links 11, connected with lever arms 12 fixed upon the shaft 13 which carries the locking-in cam levers 14. The locking-in cam levers 14 also are actuated by cams not shown in the drawing and mounted upon the cam shaft 4.

Due to the fact, that the cam levers for the sinker bar are mounted upon the same shaft as the levers carrying the needle bar 2, the sinker bar is moved in the same direction as the needle bar. The up- and down movements of the sinker bar 10 are effected by cams acting upon the cam levers of the sinker bar. The cams acting upon the the locking-in cam levers effect the locking-in movement of the sinkers.

What I claim is:

1. In a double warp knitting machine, a shaft, levers mounted on said shaft, a needle bar carried by said levers, cam levers also mounted on said shaft, double-armed levers pivoted to said cam levers, and a sinker bar carried by said double-armed levers.

2. A double warp knitting machine as set forth in claim 1 in which said double-armed levers carrying said sinker bar are connected by links to lever arms which are mounted upon a shaft carrying the locking-in cam levers.

HERBERT WIRTH.
